HARRY L. EIGENBROT, OF PITTSBURGH, PENNSYLVANIA. ASSIGNOR TO INTERNATIONAL TYPESETTING MACHINE COMPANY, OF NEW YORK, N. Y., A CORPORATION OF NEW YORK.

DISTRIBUTER MECHANISM FOR TYPOGRAPHICAL MACHINES.

1,152,718.

Specification of Letters Patent.

Patented Sept. 7, 1915.

Application filed January 9, 1914. Serial No. 811,233.

To all whom it may concern:

Be it known that I, HARRY L. EIGENBROT, a citizen of the United States, residing at Pittsburgh, in the county of Allegheny and State of Pennsylvania, have invented new and useful Improvements in Distributer Mechanism for Typographical Machines, of which the following is a specification.

My present invention relates to improvements in machines of the linotype class, and the primary object thereof is to provide an improved construction for the distributer lift cam whereby the cam may be adjusted on the distributer screw to correctly time the operation of the distributer lift relatively to the distributer screw and to compensate for wear of the cam or its coöperating roller, the cam when set being held positively, thus avoiding alteration of its adjustment and enabling a new cam to be applied readily and interchangeably to replace a worn cam.

To these and other ends, the invention consists in certain improvements, and combinations and arrangements of parts, all as will be hereinafter more fully described, the novel features being pointed out particularly in the claim at the end of the specification.

In the accompanying drawing: Figure 1 is an elevation of a part of the distributing mechanism of a machine of the linotype class, the same being viewed from the rear and the distributer lift cam being shown in section; Figs. 2 and 3 show in side elevation and end view respectively the hub for mounting the cam; Figs. 4 and 5 show in side elevation and end view respectively the cam detached from its hub.

Similar parts are designated by the same reference characters in the several views.

The present invention is applicable generally to typographical machines of the type employing a distributing mechanism where in the matrices are lifted successively into engagement with distributer conveyer screws. It is particularly adapted for use upon machines of the well known linotype class, and the preferred construction is shown in the accompanying drawing and will be hereinafter described in detail. It is to be understood, however, that the invention is not restricted to the precise construc-

tion shown as equivalent constructions within the scope of the claim can be used.

In the present instance 1 designates the distributer box which has a channel through which the lines of matrices M are fed to the upper and lower distributer screws 2 and 3 as each line of matrices comes from the casting mechanism. The matrices M are fed against shoulders 4 and 5 of the top and bottom rails 6 and 7 of the distributer box. The distributer lift operates to raise the matrices successively into engagement with the threads of the distributer conveyer screws, a matrix being lifted at each revolution of said screws. The distributer lift, as shown, embodies an arm 8 which is pivoted at 9 and has a blade 10 which engages the bottoms of the matrices successively and thereby lifts them into engagement with the conveyer screws. The arm 8 is operated by a lever 11, the latter being provided with a roller 12.

13 designates the distributer lift cam. This cam is mounted on the rear upper conveyer screw 2 through the medium of a hub 14, the latter being fixed to said screw preferably by a pin 15. The hub has a flange 16 which is provided with a circular series of apertures 17, a circular projection 18 extending beyond the face of the flange. The cam 13 is bored to fit upon the circular projection 18 and abut against the flange 16 of the hub. The cam is also provided with a pin 19 which, when the cam is in operative position, engages in one of the apertures 17 in the flange 16 of the hub. Suitable means is provided for retaining the cam in co-operative relation with the hub, a screw 20 being employed in the present instance which is threaded into the end of the hub and has its head seated in a counterbore 21 in the face of the cam.

In applying a distributer lift cam to the machine the hub 14 is fixed rigidly to the appropriate distributer conveyer screw 2 by the pin 15 and the cam is set in such a position on the hub as to cause the lifting of the matrices at the proper intervals to correctly engage the threads of the conveyer screws. Correct timing of the cam can be accomplished easily by inserting the pin 19 on the cam in the appropriate aperture 17 in the flange of the hub, this being done

- while the screw 20 is loosened, and when the correct adjustment has been obtained the screw 20 is tightened and the pin 19 will then provide a positive connection between the cam and the conveyer screw which will avoid shifting of the cam and consequent change in the timing thereof. The construction described also provides for taking up wear of the cam or its coöperating roller 12, this being accomplished by loosening the screw 20 and then advancing the cam on its hub so that the pin 19 will engage in another aperture in advance of the one previously engaged thereby. Also, when it becomes necessary to replace either the roller 12 or the cam, the cam can be readily adjusted to insure correct timing in the operation of the distributor lift equipped with the new part.
- Heretofore, the cam and its hub have been formed in one piece and permanently fixed to the distributor conveyer screw by a pin passing through the hub and screw. Rapid wear of the cam and its coöperating roller has in practice required frequent renewal of the cam owing to the incorrect timing in the lift of the matrices. It has proven difficult to replace worn cams owing to the practical difficulty of obtaining uniformity in

the location of the holes in the hub of the cam and the distributor screw for the pin. These objections which existed in machines as heretofore constructed are obviated by the present invention, as the hub of the cam is permanently attached to the distributor screw and provision is made for setting the cam thereon whereby proper timing of the parts may be produced and maintained notwithstanding wear.

I claim as my invention:—

In a typographical machine provided with means for distributing matrices therein, a separator operative to lift the matrices to deliver them in proper order to the distributor, and a cam for actuating said separator, said cam being constructed in parts adjustable to vary the point of lift and thereby secure and maintain the correct relative timing of the operation of the separator relatively to the distributor.

In testimony whereof I have hereunto set my hand in presence of two subscribing witnesses.

HARRY L. EIGENBROT.
